[57] **CLAIM**

The ornamental design for a handle for surgical instrument, as shown.

DESCRIPTION

FIG. 1 is a perspective view of a handle for surgical instrument, showing my new design, the broken line showing of the probe and connector tubing being shown in broken lines and forming no part of the claimed design;

FIG. 2 is a right side elevational view thereof;

FIG. 3 is a top plan view thereof;

FIG. 4 is a bottom plan view thereof;

FIG. 5 is a left side elevational view thereof;

FIG. 6 is a front elevational view thereof; and

FIG. 7 is a rear elevational view thereof.

Fig. 2.
